DIAMOND-POLISHING WHEEL

Julius Dinhofer, New York, N. Y.

Application December 4, 1940, Serial No. 368,429

2 Claims. (Cl. 51—109)

This invention relates to polishing wheels of the type employed for the polishing of diamonds or other gems and the primary object of the invention is to provide a polishing wheel of accurate balance; one which can be rotated at relatively high speeds without vibration or wobble, and which can be operated for long periods of time without overheating and material wear, and particularly at or adjacent to the bearings for the shaft or spindle of the polishing wheel.

Polishing wheels as constructed at the present time, are usually fixed on a vertical shaft or spindle having conical ends supported by and rotative in suitable bearings. Wheels of this character are rotated at relatively high speeds, generally about 250 R. P. M. and in some cases, at even greater speeds. Since the weight of the wheel, its spindle, the drive pulley and other elements carried on the spindle rest upon the lower conical end of the spindle, wear rapidly occurs at this end; wobble thereafter takes place in the spindle and the wheel thereupon becomes unfit for further use until a new shaft is fitted. Due to the conical shape of the ends of the spindle and the complementary supports in which these ends fit, it is difficult to lubricate these ends and the surfaces adjacent which they bear, and thus the wear above mentioned, quickly occurs.

It is the primary object of the present invention to so support the vertical shaft or spindle of the polishing wheel that the same does not rest upon nor is it supported by the conical ends on the spindle. Instead each end of the spindle is provided with shoulder portions which rest against the inner annulus of a ball-bearing which not only co-operates in providing an extremely smooth-running polishing wheel at high speed, but prevents the ends of the spindle from overheating and will enable the wheel to be run at high speed indefinitely without wobble or vibration.

In the accompanying drawing forming a part hereof, Fig. 1 is a side elevation, with parts in section, of the improved polishing wheel mechanism; and Fig. 2 is a sectional view through the lower bearing for the spindle.

With reference to the drawing, 1 indicates a supporting table or similar base, said table being provided with a circular aperture 2 in which the polishing wheel 3 rotates. The wheel 3 is secured upon a vertical shaft or spindle 4, by any suitable means and preferably by being forced thereon under pressure. At 5 is shown a goose neck bracket secured to the top of the

table 1 by means of the screws 6, said bracket being provided at its upper extremity with a boss 7 in which is adjustably mounted a bearing 8, the same being held in the selected position in said boss by means of the set screw 9. The lower end of the bearing 8 is formed with a cup-shaped member 10 within which a ball-bearing 11 is mounted. The ball-bearing is of the self-aligning type and includes an outer annulus 12 and inner annulus 13. The ball race 14 is disposed between the two annuli. At its upper end, the spindle 4 is formed with a portion 15 reduced in diameter and which snugly fits within the inner annulus 13 of the ball-bearing, the end or terminal of said reduced portion being conical and pointed as indicated at 16.

Located below the table and secured thereto by the bolts 17 is a bracket 18 provided at its lower end with a sleeve portion 19 in which is adjustably secured the lower bearing 20, said bearing being adjustable vertically, or capable of rising and lowering movement in the sleeve 19, by adjustment of the threaded cup 34 on the lower end of the sleeve 19. The set screw 21 secures the bearing 20 in position. At its upper end the bearing is provided with a cup portion 22 in which a ball-bearing similar to that previously described and shown in detail in Fig. 2, is supported. The outer annulus of the lower ball-bearing is supported upon an annular shoulder 23 formed in the cup 22, and the lower end of the shaft is formed with a reduced portion 24 fitting in the inner annulus 13. Situated adjacent the reduced portion of the spindle 4 is a shoulder 25 which rests upon the inner annulus 13 of the ball-bearing so that the weight of the spindle for the polishing wheel 3 thereon, as well as the driving pulley 26, is wholly supported upon the inner annulus 13 of the lower ball-bearing. A dust cap 27 fits over the cup 22 and prevents the entry of dust between the lower portion of the spindle 4 and the ball-bearing.

It will be noted that the lower end of the shaft at the termination of the reduced portion 24 is provided with a conical tip 28 and said conical tip is prevented from frictional contact with any portion of the bearing 20 since the bearing is recessed as indicated at 29. The spindle is driven at relatively high speed by means of a belt 30 extending from a power-driven pulley, and since the spindle is wholly supported upon and between ball bearings, it will be obvious that it can be driven at relatively high speed without wear, vibration and wobble. The coni-

cal extremities 16 and 29 at the opposite ends of the spindle are out of contact with any portions of the bearing while the device is in operation and since no wear is imposed upon these conical extremities, the same will always provide accurate centers for trueing up a new polishing wheel when it is necessary to fit a new one on the spindle 4. The ball-bearings are so disposed that the same may be quickly replaced when worn, and the effective life of the spindle is materially increased.

For the purpose of lubricating the upper bearing, a passage 30 is provided through the bearing 29, the same being provided with a nipple 31.

What I claim is:

1. In a diamond-polishing apparatus, a vertically disposed spindle and means for rotating the same, a polishing wheel on said spindle, a bracket having a portion extending below the lower end of the spindle, said bracket being provided with an internally threaded bore, a threaded shaft vertically adjustable in said bore, means for maintaining the position of adjustment of said threaded shaft, said means comprising a set screw operative against said shaft the upper end of said shaft being provided with a cup, a ball-bearing fitted within and wholly retained by said cup, said ball-bearing consisting of spaced concentric annuli with a ball race disposed between

them, the spindle having a shoulder adjacent to its lower end and a reduced portion extending from the shoulder, said reduced portion fitting within the inner annulus of the ball bearing and the shoulder resting on top of said annulus, and a ball bearing surrounding the upper end of the spindle.

2. In a diamond-polishing apparatus, a vertically disposed spindle and means for rotating the same, a polishing wheel on said spindle, a bracket having an arm extending below the lower end of the spindle, said bracket being provided with a bore, a shaft vertically adjustable through said bore, means for maintaining the position of said shaft within said bore, the upper end of said shaft being provided with a cup, a ball bearing fitted within and retained by said cup, the spindle having a shoulder adjacent to its lower end and a reduced portion extending from said shoulder and terminating in a conical end, the shoulder being supported on the ball bearing, the conical end on the spindle projecting below the lower end of the bearing and constantly maintained from frictional contact with any of the surfaces of the bearing and its support whereby wear on said conical end will be prevented and the same will always constitute a true center for the spindle.

JULIUS DINHOFER.
